Letters Patent

The schedule referred to in this Letters Patent and making a part of the same containing a description are the words of the said Jonathan T. Eastman himself of his improvement in the Cultivator for Corn and other crops, including grain, &c.

To all to whom these presents shall come,

Be it known that I, Jonathan T. Eastman of the City of Baltimore & State of Maryland have invented a new and useful improvement in the improved cultivator for corn and other crops, including grain &c., and that the following is a full and exact description thereof. Fig. 1. Represents a leg and share of a one iron cultivator. At. a, is represented a shoulder on the leg which fits nearer the bottom and front of the frame being secured to the frame by a bolt and nut, the curve of the leg must be suited to the form of the frame so as to keep the point of the share in a straight forward direction on Fig. 2. especially the leg and share detached from each other, the share being turned over to show the manner of its connection with the leg. The groove C, C, in the back of the share is neatly adapted to the form of the leg when either point of the share is placed forward.

I have drawn one hundred different cultivated cultivators for reducing the share or point of the shares, each of which has a wrought iron leg to which was attached a cast iron share by means of a dovetailing groove cast in the share and the leg turned to fit the groove without the use of a bolt. But the great difficulty attending the construction of them, is to make them fit and the insufficiency of them when so made. Must render it impossible that the instrument by such a construction can

be brought into sufficient use my object and endearments has been to simplify the construction and at the same time to render the instrument more permanent both of which objects I have satisfied myself, I have obtained in my improved construction

I claim first the construction of the leg, or shank and the manner of fastening it to the wood or frame already, the manner of attaching the shoe to the leg by means of the straight gear & bolt as shown in the drawing
